UNITED STATES PATENT OFFICE.

ROBERT REED STEWART, OF EL PASO, TEXAS.

GENERAL PACKAGE AND BOTTLE CARRIER.

Application filed July 5, 1923. Serial No. 649,604.

To all whom it may concern:

Be it known that I, ROBERT REED STEWART, a citizen of the United States, and a resident of El Paso, in the county of El Paso and 5 State of Texas, have invented certain new and useful Improvements in General Package and Bottle Carriers, of which the following is a specification.

My invention relates to package and bottle 10 carriers, and it consists in the combinations, constructions and arrangements herein described and claimed.

An object of my invention is to provide a simple and economical device affording facilities whereby a plurality of articles of various sizes and shapes may be conveniently 15 carried by hand.

A further object of my invention is to provide a device of the character described 20 which can be manufactured cheaply and which is thoroughly practical commercially.

A still further object of my invention is to provide a carrier having means for 25 releasably maintaining various articles in their desired positions while such articles are being carried by hand.

Other objects and advantages will be apparent from the following description and the novel features of the invention will be 30 particularly outlined in the appended claims.

My invention is illustrated in the accompanying drawings, forming a part of this application, in which:

Fig. 1 is a perspective view showing a 35 practical embodiment of the invention operatively applied to a plurality of articles,

Fig. 2 is an enlarged side elevation of a handle comprised in the device,

Figs. 3, 4 and 5 respectively are perspective views showing different forms of attaching elements adapted to be associated 40 with the handle exhibited in Fig. 2, and

Figs. 6, 7 and 8 respectively are vertical sections through the attaching elements exhibited in Figs. 3, 4 and 5.

In carrying my invention into effect, I provide a handle which is stamped or otherwise formed of any suitable material, preferably a light gauge metal, to have the general 50 form of a loop, such as indicated at 1 in Figs. 1 and 2. The handle 1 comprises a longitudinal grip portion 2 which is adapted to be grasped in the hand, a lower bar portion 3 which is substantially parallel with 55 the grip portion 2, and end portions 4-4

connecting the corresponding ends of the grip portion and the bar portion. As stated, the grip portion 2, the bar portion 3 and the connecting portions 4-4 are preferably made of a single piece of material and are 60 integral with one another. The bar portion 3 is provided at intervals with slots 5 which define substantially T-shaped portions 6. The latter lie in the plane of the bar portion 3. As illustrated to advantage in Figs. 1 65 and 2, the slots 5 span the heads of the substantially T-shaped portions 6 and have their ends turned toward each other to outline the heads and stems of the substantially T-shaped portions and to provide sockets or 70 seats 7-7 at opposite sides of the stem of each T-shaped portion.

Various elements may be releasably attached to the bar portion 3 and engaged with various packages, bottles, or the like, whereby all such bottles and packages can be conveniently carried by hand. In Fig. 3, I show a holder consisting of an arcuate metal strip 8 adapted to partially encircle and to embrace the neck of a milk bottle, such as 80 indicated at 9 in Fig. 1, or like article. The holder 8 has a lateral flange 10 formed thereon intermediately of its ends, which flange is provided with a slot 11 and is thus adapted to be hooked over the head of one of the 85 T-shaped portions 6. The holder 8 will be releasably attached to the bottle 9 when the ends thereof are forced toward each other so that the holder tightly embraces the bottle neck and are secured in such position by 90 means of a chain 12 secured at one end to an end of the holder 8 and adapted to engage a notch 13 in the other end of the holder.

The fastening element illustrated in Fig. 95 4, comprises a curved plate or strip 14 having laterally extending ears 15-15 at the upper corners thereof and prolongations or extensions 16-16 at the lower corners thereof. The prolongations or extensions 16-16 are provided with openings 17-17 through which a flexible suspension element, such as the chain 18, may be threaded. The ears 15-15 are provided with notches 19-19 with which portions of the chain 18 may be detachably engaged. As illustrated in Fig. 1, the chain 18 is threaded through the openings 17-17 and the ends thereof are secured together so that the chain is in effect 100 an endless member. The fastening element 110

14 is curved to conform to the curvature of the neck of a bottle, such as indicated at 20. The chain 18 and the fastening member 14 are arranged in encircling relation to the neck of the bottle 20. The chain 18 is then drawn tightly against the bottle neck and is placed in engagement with the notches 19-19. The chain 18 is then hooked over a selected one of the substantially T-shaped portions 6 and the bottle 20 will thus be suspended from the handle 1 when the latter is carried by hand.

In Figs. 5 and 8, I show another attaching element consisting of a hook member 21 adapted to engage the binding cord 22 of a package, such as indicated at 23 in Fig. 1. The hook member 21 has a body provided with a pair of upstanding ears 24-24, each having an opening 25 formed therethrough. The hook member 21 is suspended from the handle 1 by means of a flexible suspension member, such as the chain 26 which has portions thereof threaded through the openings 25.

In Fig. 1, I show a jar 27 suspended from the handle 1 by means of an endless suspension chain 28 which is secured in encircling relation to the neck portion of the jar and is hooked over a selected one of the T-shaped portions 6.

It is to be observed that in each instance in which a suspension chain of the construction illustrated is used in attaching articles to the handle 1, that the portion of the chain disposed in the seats 7-7 will engage with the head and stem of the substantially T-shaped portion 6 to prevent the suspension element from being accidentally detached from the handle, while permitting such suspension element to be disengaged from the handle readily when desired.

It will thus be obvious that I provide a simple device for carrying a plurality of articles whereby such articles will be maintained in upright position so that the contents thereof will not be spilled.

Obviously, my invention is susceptible of embodiment in forms other than that which is illustrated in the accompanying drawings, and I therefore consider as my own, all modifications and adaptations of the form of the device disclosed herein which fairly fall within the scope of the appended claims.

I claim:—

1. In a device of the character described, 55 a fastening element consisting of an arcuate strip provided intermediately with a laterally extending flange having an aperture therein, said arcuate element having a notch in its upper edge adjacent to one end 60 thereof, and a chain attached to the other end of the arcuate strip and adapted to engage the notch, substantially as and for the purpose described.

2. In a device of the character described, 65 an attaching element consisting of a plate curved to conform substantially to the curvature of a bottle neck and having prolongations at the lower corners thereof and laterally extending lug portions at the upper corners thereof, said prolongations being provided with openings through which the chain may be threaded and said laterally extending lug portions being notched and being adapted to be engaged by the 75 chain.

3. In a device of the character described, a handle comprising an upper horizontal grip portion, a lower flat bar member connected at its ends to said grip portion, and 80 suspended vertically edgewise from the grip member, substantially in parallel relation to the latter, said lower bar member being formed with a slot therein between the lower and upper edges thereof, said slot having 85 the intermediate portion thereof extending longitudinally of the bar and having the end portions thereof turned vertically downward and then inward toward each other to define a substantially T-shaped supporting 90 element, the inwardly turned extreme end portions of the slot constituting sockets adapted to engage with a flexible suspension element which has been hooked over the T-shaped supporting element. 95

4. In a device of the character described, an attaching member comprising a flat body bent adjacent to one end into hook shape, the body having a notch in the other end thereof dividing said other end portion 100 thereof into a pair of spaced apart ears which are disposed in substantially the same plane, each of said ears having an opening therethrough, as and for the purpose described.

ROBERT REED STEWART.
